PRINTING WHEEL

James G. McKay, Chicago, Ill.

Application February 23, 1950, Serial No. 145,660

3 Claims. (Cl. 101—376)

1

This invention relates generally to printing wheels and more particularly is directed to a novel construction for a printing wheel of the type to be used for printing dates, classifications and other indicia on moving packages of a production line, for example.

My invention is suitable for use in the production of printing wheels in many different types of dating and numbering devices where it is required that the numbers or letters be changed frequently without difficulty and without unduly delaying the movement of the production line. In achieving the construction of a wheel which will enable these functions to be performed in a speedy and highly efficient manner I have accomplished one of the principal objects of my invention.

Another object of the invention is to provide a wheel which has knurled edges for engaging the packages as the wheel rolls over the same, which knurling is extremely deep thereby deforming the said edges to extend laterally providing a shoulder cooperating with other portions of the wheel to hold type members.

Another object of the invention is to provide a printing wheel of the character described in which the body of the type is protectively mounted below the edges so that the edges of the wheel take the brunt of the pressure of the printing wheel against the package from the type to cause said type to last a relatively long time.

Still a further object of the invention is to provide a novel construction of the printing wheel to enable same to be manufactured cheaply and with a minimum of parts and utilizing simple tools.

Other objects of the invention lie in the provision of novel constructional features of my invention which will be pointed out as the description of the preferred embodiment proceeds.

I have illustrated a preferred manner of carrying out my invention whereby many advantages and objects not specifically enumerated will become apparent.

In the drawings:

Fig. 1 is a side elevational view of a printing wheel having numberers associated therewith in addition to print members, which wheel is constructed in accordance with my invention, parts being shown in section to illustrate details.

Fig. 2 is a top plan view of the same.

Fig. 3 is a sectional view taken through the printing wheel of Fig. 1 and looking in the indicated direction, but showing the lower end of the wheel engaging a surface upon which characters are being printed.

2

Fig. 4 is a sectional view taken through the wheel generally along the line 4—4 of Fig. 3 and in the indicated direction, but showing the manner in which the knurling engages the surface and the manner in which the circumferential type members engage beneath the shoulders formed by the knurling, the view being on a greatly enlarged scale.

Fig. 5 is a side elevational view of a modified form of a printing wheel which is simple in construction in that no numberers are included, said wheel embodying my invention.

Fig. 6 is an edge view in elevation showing the form of type members used with the constructions described prior to associating same with the printing wheel.

The invention resides principally in the provision of the deeply knurled circumferential edges of the face plates of a printing wheel thereby providing not only means for frictionally engaging the surface to be printed to cause rotation of the wheel, but also providing shoulders beneath which type members may be engaged and firmly held, while serving to limit the amount of deformation of the type members during printing to cause same to wear better than heretofore. The printing wheel is capable of being used with apparatus described in my co-pending applications Serial No. 789,239, filed December 2, 1947, now Patent No. 2,562,627, for Device for Printing Characters, Etc. and Serial No. 145,659, filed February 23, 1950, for Code Printing Attachment for Tape Dispensing Machines, although not being limited thereto. The invention is applicable to simple wheels having only the type members hereinafter described, and as well to wheels which in addition have the numberers shown and described in the former of said co-pending applications.

Referring now to the drawings, the reference character 10 designated generally a printing wheel formed of a pair of spaced apart circular face plates 11 mounted upon a bushing 12 by means of the opposite nuts 13 threaded to said bushing 12 and having a central shaft 14 journalled in said bushing. Such printing wheels as described herein are usually mounted idle so that as a surface 15 moves relative thereto, the wheel will rotate printing characters upon said surface. Such idle mountings are well-known in the arts and need not be illustrated herein but are shown in my co-pending applications hereinabove referred to. The face plates 11 are provided with aligned rectangular openings 16 circumferentially arranged and radially disposed,

and a numberer 17 is disposed between each pair of aligned openings 16 having the frame members 18 thereof engaged by the inner surfaces of the plates 11 so that the plates 11 are spaced apart by means of such frames.

The details of construction of such numberers form no part of my invention, but suffice it to say that same may be the conventional rotatable tape form of numberer modified to be associated with the printing wheel 10 in accordance with the disclosure of my co-pending application Serial No. 789,239 and having the exposed printing characters 19 slightly protruding beyond the circumferential edges of the wheel 10 so that as said wheel is rotated the characters 19 will be impressed upon the printing surface 15.

The plates 11 are held together upon the frames 18 by a plurality of bolts 20 and 21, the bolts 21 also serving another purpose to be described.

The circumferential edges of the plates 11 are knurled, as shown at 22, but instead of knurling the said edges in the conventional manner, said edges are provided with an exceedingly great knurling. The effect is that not only is a deep and pronounced knurl provided, but as well a portion of the edge is deformed laterally thereby providing a sharp undercut flange or shoulder on opposite sides of the plates 11 along the circumferential edges thereof. The outer shoulders 23 are of no importance, but the inner shoulders 24 which face one another are an important portion of my invention. Said inner shoulders 24 may be formed in other manners than knurling, but I prefer the method because of its great economy and the need for a minimum of forming tools.

Said shoulders 24 serve to retain the flexible type strips 25 in the circumferential slots of the wheel 10. The type strips 25 are formed as shown in Fig. 6 of strips of flexible material such as rubber having the characters 26 and their backings 27 vulcanized thereon. The width of the strips 25 is exactly the distance between the inner faces of the plates 11, and the height of the strips up to the backing 27 is equal to the depth of the slots from the surface of the arcuate members 29 to the base of the shoulders 24, that is to the juncture of the inner face of the plates 11 with said shoulders 24. Said slots which are designated 30 are formed by means of a plurality of arcuate straps 29 spaced inwardly of the knurled edges 22 and extending between the numberers 17 so that type strips 25 may be disposed between said numberers. The ends of the straps 29 are curled around the bolts 21 as shown at 31 especially in Fig. 1.

The strips 25 are formed with a plurality of cuts 32 between the characters 26 to enable the normally flat strips 25 to be arched when installed upon the printing wheel. The strips are forced into the slots 30 so that their edges are engaged beneath the knurled shoulders 24 in the slots 30 as shown in Figs. 3 and 4. The base of the strip 25 is snugly engaged against the strap 29, holding the strip in place.

As the wheel 10 engages the surface 15, the frictional engagement between the knurled edges 22 and the said surface causes the wheel to rotate. The wheel cooperates with an inking device (not shown) which daubs the characters 19 and 26 with ink as the wheel passes the same and thereafter transfers said ink to the surface 15. When the characters 26 engage the surface 15, the same are compressed, as shown on the

bottom of Fig. 3, but such compression is limited by the edges 22 of the wheel 10 thereby providing little wear and long life for said strips 25. Furthermore the characters are less distorted and print clearer than other devices.

In Fig. 5 I have shown a form of printing wheel which is greatly simplified. Same is designated generally 50 and consists of a pair of circular plates 51 mounted upon a shaft 52 and held in spaced relation by a concentrically arranged sleeve 53 which serves as a spacer. The sleeve is positioned by the sleeves 54 carried by the fastening bolts 55. The edges 56 of the plates 51 are knurled in the exact manner as the edges 22 thereby forming similar undercut shoulders 57. Obviously a continuous type slot 58 is thereby formed about the wheel 50 between the sleeve 53 and the edges 56.

I dispose type strips 25 in the slot 58, symmetrically spaced about the circumference of the wheel so that equally spaced impressions will be obtained, for example upon an endless paper tape. To assist in such spacing and to prevent the type strips from slipping along the slot I provide stop members in the slots, such as the transverse pins 60 against which the ends of the strips 25 may be engaged. Thus in Fig. 5, the wheel 50 is intended to rotate in a clockwise direction so that the pins 60 will prevent movement of the strips 25 relative to the slot 58. Obviously the strips 25 are engaged in the identical manner as those described in connection with Figs. 1 to 4 inclusive, and the same advantages are achieved.

It should be obvious that the characters 26 need not be formed in strips but may be individual flexible members deformable sufficient to be readily removed or installed in the wheels. My invention contemplates either or both of these expedients.

It is believed that my invention and the preferred manner of constructing the printing wheels described herein have been explained sufficiently to enable those skilled in the art to understand and appreciate the advantages and benefits thereof. Many variations are possible with respect to size, shape, and other details, but I do not wish to be limited by the description except as circumscribed by the appended claims.

I claim:

1. A rotatable printing wheel for printing indicia on a printing surface moving relative thereto which comprises a pair of spaced apart discs, means sandwiched between the discs and forming therewith a circumferentially arranged slot therebetween, a flexible type strip member removably disposed in said slot and having characters protruding beyond the edges of said discs, the circumferential edges of the discs having knurling therealong of sufficient depth to provide without undercutting of the side faces, relatively long deformed lateral juxtaposed shoulders engaging over the upper edges of the strip member at points radially spaced inwardly of said circumferential edges whereby to fix the strip member in the slot and limit the extent of compression of said characters when pressed against said printing surface.

2. A construction as set forth in claim 1 in which the means sandwiched between the discs comprises a sleeve member having a diameter substantially less than the said discs and arranged concentrically thereof.

3. A construction as set forth in claim 1 in

5

which the said slot is provided with means to limit slippage of said strip member therealong.

JAMES G. MCKAY.
